Application December 12, 1934, Serial No. 757,092

13 Claims. (Cl. 261—76)

This invention relates to a method of and apparatus for gasifying a liquid or plastic fuel, its primary object being to form therefrom a homogeneous gaseous fluid for use in various types 5 of combustion devices.

In preparing either liquid or plastic fuels for combustion purposes, particularly for use in internal combustion engines and burners, the method universally employed consists of transforming 10 the liquid into a vapor or mist by more or less conventional atomizing or vaporizing devices, and then combining the resulting spray with air to obtain a mixture in explosive proportions. It is the obvious aim of every atomizing device of this 15 class, such as carburetors and the like, to produce as fine a spray as possible; but even in the most efficient devices of this kind, where an exceedingly finely-divided spray is obtainable, the fuel stream is nevertheless composed of air-carried liquid particles, constituting a mixture that 20 is noticeably wet particularly at the relatively low intake manifold temperatures of internal combustion engines. In conceiving this invention it was our purpose to improve upon this condition and to effect a finer degree of pulverization of 25 the liquid than has ever heretofore been obtained; and in a mechanical embodiment of our invention and the process employed thereby we have succeeded in obtaining from hydrocarbons, and from 30 relatively heavy and low-volatile fuels, in accordance with one of our objects, a product that is or has every apparent characteristic of a homogeneous fixed gas,—one which is invisible and substantially dry at intake manifold temperatures. 35 Although some attempts have been made in the past to gasify liquid fuels, the nature of the means employed therefor necessitated the use of fuel pre-heating methods resulting, in several instances, in the production of a relatively impure gas, such as one mixed with the products of 40 combustion; and it is our belief, from a study of the prior art and a knowledge of commercial devices in this category, that this is the first successful method devised for the production, from a liquid fuel, of a fixed gas that can be free from the 45 products of combustion, and that is adaptable for use in such combustion devices as internal combustion engines, burners and the like.

Briefly, the method we employ for accomplishing the above-described result includes, as the first essential step, the directing of a spray of liquid fuel, induced in part by a continuous current of an atomizing medium such as preheated air, into a flow conduit comprising a longitudinal series of tubes of successively increasing diam-

eters, with overlapping adjacent ends in fixed telescopic arrangement, the tubes being preferably of the Venturi type and the said overlapping ends being in spaced relation to form circumferential gaps therebetween. The said current of 5 preheated air is then caused to pass about and along the outer peripheral surfaces of the first few tubes in substantially cylindrical concentric streams, entering a predetermined number of 10 said circumferential gaps to commingle with the inner fuel stream, thereby effecting an interpenetration of the constituents of said latter stream with that of fresh currents of heated air at a 15 number of points. A continuous fresh stream of relatively cold air is then introduced along the 20 succeeding peripheral surfaces of the last few tubes to enter the remaining of said gaps and similarly commingle with the inner stream, thereby diluting it a predetermined amount in accordance with combustion requirements.

The fuel stream, during its path of travel 25 through the tubes, successively passes through a plurality of intensely evaporative regions of local vacuum at the constricted portions of the venturis, with resulting lowered boiling points and the consequent complete gasification of any suspended fuel particles by the heat in said concentric streams of air. The temperature of the fuel 30 in its initial liquid form is below its evaporation range, so that no fractional distillation takes place at the beginning of the process; but the preheated air (or other hot atomizing fluid), however, is of a temperature above the boiling point 35 of any of the constituents of the fuel at the reduced pressures prevalent at the throats of the tubes, assuring complete gasification when the fuel stream has passed a number of venturis. This gasifying action is materially aided by a pulsating effect throughout the fuel stream, produced by the alternate contraction and expansion 40 of the stream and its periodic changes in velocity due to the successive variations in cross-sectional area of the tubes and the heat-transfer influence of the injected air,—thereby creating such interpenetration, turbulence and molecular 45 impact within the gas as to make for homogeneity. The fuel stream, as stated, is subjected to successive expansion stages, which, together with the effect of the cooling air introduced as aforesaid, results in a relatively low gas temperature 50 at the outlet of the device,—below the vapor condensation point of the gas at the prevailing pressure,—a condition which, in internal combustion engines, is obviously conducive to high volumetric efficiency.

The above-described process is flexible in nature, and is adapted to produce a hydrocarbon gas in various degrees and proportions of fixity, which is in accordance with another object of 5 our invention.

Another object of this invention is to generate a gaseous fluid from a heavy as well as a light fuel oil with such rapidity as to produce a practically instantaneous gasifying action, a feature 10 invaluable in starting internal combustion engines at low temperatures.

Still another object of this invention is to automatically vary the relative proportions of the gaseous fuel and a fluid such as air, thereby obtaining a predetermined fuel ratio over any required range in conformity with the demands of 15 the fuel-consuming device, such as an internal combustion engine, a gas burner or the like.

A further object is to produce an apparatus for 20 employing the above-described process which is sufficiently compact as to be adaptable for use on motor cars and other places where space economy is an important consideration.

And another object of our invention is to effect 25 a cracking of fuel oil by means of our said process, a result which is obtained by employing a pre-heating medium (used in conjunction with a step of the process) of a temperature sufficiently high to accomplish this purpose for the fuel used.

30 Other objects, features and advantages will appear from the drawings and the description hereinafter given.

Referring to the drawings,

Figure 1 is a vertical sectional view of the principal unit of one form of apparatus employing the process constituting part of this invention.

Figure 2 is an enlarged sectional view of a portion of the apparatus of Figure 1, illustrating the paths of the fuel and air streams.

40 Figure 3 is a sectional view of the spraying portion of another form of our apparatus, showing a single venturi with a serrated outlet edge.

Figure 4 is a view similar to Figure 3 showing a modification with a two-stage venturi.

45 Figure 5 is a sectional view of another form of our invention showing a multi-stage venturi all the tubes of which have serrated terminals, this arrangement showing an atomizing and a cooling section.

50 Figures 6 and 7 represent a sectional elevation and plan view respectively of a fuel jet with a smooth peripheral outlet edge, adapted for use with our apparatus.

Figures 8 and 9 show a section and plan respectively of a jet with a serrated edge.

55 Figures 10 and 11 are sectional and plan views respectively of an oil jet with a slotted wall.

Figures 12 and 13 are sectional and plan views respectively of a jet with a combined slotted and 60 serrated outlet portion.

Figure 14 is a fragmentary sectional view of a combined jet and spray device adaptable as an adjunct to the apparatus constituting part of this invention.

65 Figure 15 is a sectional view of another form of oil spray jet.

Figure 16 is a sectional view of a modification of our invention illustrating a method of varying the ratio of the heated atomizing fluid medium 70 to the cooling air required for combustion.

Figure 17 is a section of Figure 16 taken along line 17-17.

Figure 18 shows a form of outlet passageway for the fuel stream.

75 Figure 19 illustrates a form of heat exchange

apparatus for preheating the atomizing air, comprising an exhaust pipe of an internal combustion engine surrounded by an air supply jacket.

In the drawings, the casing 30 contains therein the flow conduit 31 comprising a plurality of tubes 32, 33, 34, 35, 36, 37 and 38 of successively increasing diameters and preferably of the Venturi type, these being longitudinally disposed with overlapping adjacent ends to form a plurality of circumferential gaps 39, 40, 41, 42, 43 and 44. The said 10 flow conduit 31 is divided into two sections by the partition 45, said partition being so arranged with reference to the tubes, in the particular design shown, that the said gaps 39 and 40 are contained within the atomizing inlet 46, and the remaining 15 gaps are contained within and communicate with the combustion air inlet 47. The said inlets 46 and 47 are provided with suitably controlled valves 48 and 49 respectively. The fuel nozzle or 20 jet 50 is operatively adjacent the inlet to the tube 32, said jet being supplied with fuel drawn in through pipe 51 which extends into the float bowl 52,—the needle valve 53, controlled by the adjustment screw 54, being operatively engageable with the inlet terminal of pipe 51. The said flow 25 conduit 31 communicates either with a combustion chamber of a burner or with an intake manifold of engine 55 through the valve 56. It will be noted that in the apparatus disclosed in Figure 1 the first three tubes have serrated outlet edges, 30 the balance of the tubes having their corresponding outlet edges of smooth configuration.

Although the form of apparatus of Figure 1 shows a series of seven venturis, it is also within the contemplation of our invention to employ 35 various other arrangements, such as the single venturi 3a as illustrated in Figure 3, a double venturi containing the tubes 4a and 4b as shown in Figure 4, or a longitudinal arrangement of a plurality of venturis in any number as design 40 requirements may dictate. It is also within the contemplation of our invention to employ venturis with any predetermined number of serrated outlet edges, depending upon design and engineering requirements, such as the apparatus of Figure 45 5 where all of the venturis 5a, 5b, 5c, 5d, 5e, and 5f are shown with serrated edges. And it should be further noted that the flow conduit 31 of our invention need not necessarily be divided into two sections by a partition such as the wall 45 requiring the use of two fluid mediums, as a single 50 fluid medium can be employed within the scope of our invention, for ordinary carburetion purposes, as indicated in Figure 2, and such a construction can be employed in a down-draft device 55 with the flow conduit extending vertically as shown in Figure 5.

Although the flow conduit referred to in the drawings and description herein comprises mainly venturis of substantially cylindrical shape, 60 other forms of tubes can be employed within the scope of this invention, such as those of conical configuration or of square or rectangular cross-section. Also, instead of circumferential gaps in planes normal to the conduit axis, helically disposed gaps or other forms of inlet ports can be 65 employed within the intent of our invention.

The spray nozzle 50 may be of the design illustrated in Figures 6 and 7 with a smooth terminal edge 6a; or it may be one having serrated edges 70 8a such as is shown in Figures 8 or 9. In Figures 10 and 11 is shown a spray nozzle the sides of which contain a plurality of slots 10a,—and in Figures 12 and 13 another form of nozzle is shown, combining the features of a serrated and 75

slotted nozzle wall, and containing the slots 12a and serrations 12b.

In the operation of this device, a flow of fuel is induced through the nozzle 50 into the tube 32,—the amount of said fuel being regulated by the needle valve 53. A heated medium, such as air suitably preheated, is caused to flow through the valve 48 and inlet 46 to enter the tube 32, thereby serving to form an atomized fuel stream 10 within the flow conduit 31. The said atomizing medium or preheated air also passes over and surrounds the tubes 32 and 33, entering the gaps 38 and 40 to commingle with the said fuel stream within the multi-tube conduit. In the form of 15 our invention shown in Figure 1, relatively cold combustion air is caused to enter the inlet 47 through the valve 49, such air similarly entering the gaps 41, 42, 43 and 44 to further commingle with the fuel stream which is headed to enter 20 the intake manifold of engine 55 through the valve 56. Reference to Figure 2 will show the paths of flow of the various fluid streams.

The term "combustion air" as herein employed is used to identify the unheated and uncontaminated fluid medium entering the flow conduit through inlet 47, as distinguished from the fluid medium entering through inlet 46. Although the latter fluid generally also contains combustion air, it serves the primary purpose of an initial 30 atomizing medium, being preferably preheated, and at times mixed or "contaminated" with a hot gaseous fluid.

An analysis of the action within this apparatus will disclose, as will be more specifically hereinafter pointed out, that the method employed thereby embodies several steps all of which coact combinatively to convert a liquid fuel into a gas and to impart thereto the properties of combustibility, homogeneity and such low temperature 40 characteristics as are conducive to high volumetric efficiency. The said steps are both mechanical and thermodynamic in nature,—the mechanical steps comprising or effecting (a) induced ejection of the liquid fuel, (b) atomization there- 45 of by a fluid medium such as air, (c) dispersion from the peripheral terminal edge of the fuel nozzle and from a plurality of successive edges or points along the path of travel of the fuel stream, (d) interpenetration of a number of fluid 50 streams with the inner fuel stream due to their intersecting paths of travel, (e) molecular disturbance and turbulence within the fuel stream due to variations in the cross-sectional areas of the flow conduit and to the consequent changes 55 in velocity and successive contractions and expansions of the fuel stream along its path of travel, (f) gradual and progressive dilution of the fuel stream at different points along its path with fresh supplies first of the atomizing medium and 60 then of the combustion air, (g) and progressive expansion of the fuel stream effected by the increasing cross-sectional area of the flow conduit; and the said thermodynamic steps comprising or effecting (h) a direct heating of the fuel stream 65 with consequent increased kinetic energy and turbulence within the stream, (i) alternate contraction and expansion of the fuel stream at a number of points along the flow conduit produced by the mixing of the fuel stream with 70 relays of atomizing fluid or air of different temperatures and all within a confined region, thereby creating internal molecular activity and agitation and (j) complete evaporation of the liquid 75 particles comprising the fuel stream by the heat of the preheated air or atomizing medium at the

constricted portions or throats of the flow conduit where the low-pressure conditions cause a lowering of the boiling point of the fuel stream.

Specifically, the liquid fuel is drawn into the flow conduit 31 partly through the induced action 5 of the preheated air or other fluid medium entering through valve 48, thereby converting the liquid fuel into an initial state of atomization. As the fuel leaves the nozzle 50, it will be dispersed forwardly from the peripheral terminal edge 10 thereof. Where a spray nozzle having a serrated edge such as 8a disclosed in Figures 8 and 9 is employed, the liquid is torn from each of the many points on the skirt of the nozzle, thereby resulting in a spray considerably finer than would 15 be the case where the liquid were ejected from a smooth outlet terminal or one with relatively few points. Where the nozzle of Figures 10 and 11, or of Figures 12 and 13 is employed, the slots in the wall of the nozzle present a greater outlet 20 surface for the liquid fuel being ejected, thereby effecting a greater degree of initial atomization. As the fuel stream continues through the flow conduit, it must necessarily pass each of the 25 terminal ends of the longitudinally disposed venturis, and where these terminal edges are also serrated, there will be a still greater atomizing effect, inasmuch as any liquid particles that may collect thereon will be torn from a great plurality 30 of points to produce a greater degree of pulverization.

It will be noted that the streams of atomizing fluid or air surrounding the Venturi tubes, in entering through the circumferential gaps therebetween, follow a path intersecting that of the 35 direction of flow of the inner fuel stream (see Figure 2), thereby causing an interpenetration of the entering fluid with said inner stream,—a condition which is considerably enhanced by the fact that the entering fluid is injected into a 40 fluid traveling at a relatively high velocity due to the constrictions of the venturis at the throats thereof. Such interpenetration is quite obviously conducive to a greater pulverizing effect. The inner fuel stream is also subjected to considerable turbulence due to the variations in the cross 45 sectional area of the flow conduit throughout the length thereof, inasmuch as said stream must successively pass through a series of Venturi constrictions; and such cross-sectional variations 50 produce velocity changes and successive expansions and contractions of the stream, bringing about a considerable internal disturbance to effect a thorough mixing.

Another very important factor in this gasifying process is the method of gradual dilution of the fuel stream with the mixing fluid simultaneously injected at a number of different points,—especially when there is first the introduction of the atomizing medium such as preheated air 55 through the first series of gaps, and then the introduction of secondary or unheated combustion air through the remaining gaps. At each of said gaps a stage in this gradual dilution process is effected; and at each stage there is introduced a 60 fraction of the entire predetermined amount of fluid required. This method of gradual dilution by the introduction of the fluid in instalments is obviously very conducive to thorough mixing. It should further be noted that this multi-stage 65 method of continuously introducing a fluid medium such as preheated air and combustion air has the further advantage of supplying to the fuel stream, at each point of injection, charges 70 of relatively fresh and uncontaminated air. 75

which is always preferred for combustion purposes. And by employing this method, no stratification of air in the fuel stream will take place, such as generally occurs when all the combustion air or other fluid medium is introduced at one time in one local region.

Each successive venturi, as can readily be seen, is of greater diameter than the preceding one, thereby constituting a gradually expanding flow conduit 31,—an arrangement which permits of the progressive expansion of the fuel stream with a resultant relatively low temperature at the intake manifold, a condition which is aided by the heat-transfer effect of the cooling air introduced through valve 49. From tests which we have conducted, we have noted temperatures in the intake manifold considerably below the condensation point of the gaseous fuel fluid, without any visible evidence of precipitation,—the fluid being absolutely invisible. This low temperature, which is obviously conducive to high volumetric efficiency as hereinbefore stated, is due in part to the relatively low temperature of the incoming combustion air, but is primarily brought about by the refrigerating effect of the successive expansions of the fuel fluid stream in passing through the venturis.

Another advantage of employing venturis with serrated terminals positioned in the throats or restricted regions of succeeding venturis is the readiness with which the venturis can be adjustably positioned for best operation. It is evident that the roots and apices of the serrations in a given venturi are situated in two different planes, presenting outlet edges extending substantially longitudinally of the flow conduit. The arrangement hence is not as critical as would be the case in a venturi with a smooth terminal edge, inasmuch as the serrated edge can be moved slightly in a longitudinal direction without materially affecting the results, provided the said outlet edges are within the region of the throat of the venturi. Hence in such a construction non-fluctuating pressure conditions can be more readily attained, with a consequent steady flow of the fuel stream.

Other essential factors which are accountable for the gasifying action of our process relate to the effects of prevailing heat and pressure conditions therein. It is well known that the pre-heating of the fuel stream will aid the pulverization process by virtue of the greater internal molecular activity generated within the stream; and as a heated fluid is introduced into the fuel stream through valve 48, such action is effected in our apparatus. Furthermore, the introduction of atomizing and combustion air fluids of varying temperatures through the gaps between the tubes causes a heat exchange to take place at each region where there is a gap, resulting in an expansion of the heat-absorbing fluid and a contraction of the heat-emitting fluid. Inasmuch as both of these co-mixing fluids are contained within a confined portion of the flow conduit, this simultaneous expansion and contraction of both fluids will cause a very desirable condition of intermingling.

From actual tests which we have conducted, we have found that the depression at the throat of the first venturi 32 is considerably in excess of the manifold depression, the depressions at the throats of the intermediate venturis being in proportion. As a matter of actual experimental observation, we have noted that with a manifold depression of 3" of Hg the depression at the

choke band of venturi 32 is approximately seven times as great. It is hence obvious that the boiling point of the fuel at the constriction in venturi 32 is materially lowered beyond its normal atmospheric value. Inasmuch as the pre-heated fluid entering through the valve 48 is limited only to temperatures which will disintegrate or adversely affect the metals constituting this device, such temperatures can be relatively high since such metals can be of high heat-resisting properties. It is therefore obvious that the incoming fluid through valve 48 can be of sufficiently high temperature to completely evaporate any liquid particles of oil suspended at the low-pressure region of the throat of venturi 32; and this applies to a wide range of fuels including those of heavy and low volatile characteristics, such as are used in furnaces for domestic heating and industrial purposes. If the temperature of the incoming fluid is greater than the end point of the fuel at the prevailing low pressure within the venturi, it is apparent that there will be a complete evaporation of every particle of liquid, without any fractional distillation whatsoever. Any surface tension of the fuel or liquid particles constituting same which may tend to resist gasification will be completely counteracted by the shocks imparted to the fuel stream by the repeated sudden changes to low pressure conditions at the Venturi constrictions.

From the above detailed description of the mechanical and thermodynamic actions within our apparatus, as effected by the steps of our process, it becomes obvious that a fuel stream is generated thereby which is subjected, at a number of points along its path of travel, to manifold gasifying conditions, resulting in a fixed homogeneous gas that is relatively dry at manifold pressures and temperatures, and which is of a sufficiently low temperature for high volumetric efficiency in an internal combustion engine. And where the preheated air or other preheating medium is of a sufficiently high temperature, in accordance with the requirements of the particular fuel used, an actual cracking of the fuel will be effected. Furthermore, it is apparent that the entire gasifying or cracking process takes place within a relatively small space,—the entire action being practically instantaneous, and hence operably effective with both heavy and light fuels at exceedingly low temperatures.

It should be noted that although the term "liquid fuel" is repeatedly referred to, throughout this specification and the claims hereinafter set forth, as the fuel to be converted to a gaseous fluid by means of this invention, it is in the broader sense that this term is used, the intent being to include in its category colloids and plastic fuels as well.

In order to effect a more efficient initial atomization, we have conceived the modified form of combined spray and nozzle illustrated in Figure 14, as an adjunct to this apparatus. In this modification the double opposed spray nozzles 57 and 58 are operatively positioned adjacent the openings of the venturis 59 and 60 respectively. Intermediate said venturis is an auxiliary air supply duct 61 which introduces a supply of air transverse to the direction of flow of fuel through said nozzles. When the opposing streams from these nozzles meet, and the combined stream is diverted downwardly through the venturi 62, a greater soaking period is obtained, due to the time consumed in effecting this directional change and

to the further fact that as said opposing streams approach each other their velocities become considerably reduced. To effect still greater initial atomization the stream of air injected through the duct 61 is heated, imparting to the combined stream an additional amount of heat beyond that supplied by the initial atomizing air.

Another modification of spray nozzle is illustrated in Figure 15 in which the two funnel-shaped walls 63 and 64 form therebetween a funnel-shaped space 65 into which the oil from supply tube 66 enters to be discharged through the peripheral opening 67. Atomizing air, preferably preheated, is fed into a tube 68 and discharged through orifices 69,—this air not only assisting in heating the fuel oil pulverized from the outer serrated edge of the nozzle, but also serving to eliminate the vacuous zone created in the hollow of the cone. With this design, the fuel oil is kept confined to the outer peripheral edge of the nozzle, thereby insuring a finer degree of atomization than could be effected if some relatively large particles of liquid fuel were permitted to drop through the center of the cone.

In order to vary the proportion of the atomizing medium such as preheated air to the cooling medium such as combustion air, we have provided the flow conduit forming part of this invention with a variable valve arrangement such as is disclosed in Figures 16 and 17. At each circumferential gap of the longitudinal series of venturis there is a wall, such as those identified by the numerals 70, 71, 72, 73 and 74 forming therebetween fluid inlet channels 75, 76, 77, 78 and 79. A hollow shell or valve 80 is slidably mounted over the wall of the inlet duct 81 and adapted for slidably engagement with the outer terminal portions of said walls 70, 71, 72, 73, 74 and the wall 82. Upon a slidable manipulation of said valve 80, the number of said channels 75, 76 etc. exposed to and communicating with the inlet duct 81 can be varied in predetermined manner. Thus, in the position illustrated in Figure 16, the fluid entering duct 81 can enter the channels 75 and 76, whereas the channels 77, 78 and 79 are exposed to and communicate with the incoming cool combustion air. By moving the valve to the left, a greater proportion of the atomizing fluid flowing through duct 81 is permitted to enter the said channels, thereby supplying a greater number of venturis with the heated fluid medium,—and only a proportionally smaller amount of cooling air can enter. It will thus be seen that the mixture ratio of fuel to air may be regulated as to weight and final volume by a manipulation of the valve 80. For example, if said valve is moved to the left to admit more preheating fluid and less cooling air, the final mixture ratio would be richer, and conversely if the slide were moved to the right so as to admit more cooling medium the final mixture ratio would be leaner. In this manner, not only may the degree of fixation be controlled while the gasifier is in operation, but a greater degree of gasification will be effected over a larger fuel range.

It should be noted that although our apparatus and process are herein repeatedly referred to as being adapted for use with two fluid mediums of different temperatures, they are equally well adaptable for use with a single fluid medium, such as preheated air,—an arrangement which is highly desirable in certain types of fuel-burning installations. For example, if the slide 80 of Figure 16 were moved to its extreme left posi-

tion, all the cooling air would be excluded, and only preheated air allowed to enter the apparatus,—thereby permitting the use of lower temperatures of the preheating medium for the production of a gas in combustible proportions.

For the purpose of producing a greater degree of homogeneity of the gaseous fluid as it leaves the last venturi and before it enters the intake manifold, we have devised a modification of the intermediate passageway between the last venturi 10 of the flow conduit and said manifold. In Figure 18, the last venturi 83 having the serrated edge 84 leads into the chamber 85 containing an expanded portion adjacent the venturi and tapering downwardly to the manifold inlet diameter at 86. 15 With such an arrangement, the discharge from the venturi 83, at its relatively high velocity, will cause the fluid to move in a swirling direction as indicated by the arrows, thereby causing the reverberation of the outer zone of the fuel stream 20 and a more thorough mixing thereof. It should be noted that in this construction the expanded portion of the chamber 85 completely surrounds the outlet end of the venturi 83 which protrudes 25 into the chamber.

In the above description of the apparatus and process employed thereby, we have repeatedly referred to preheated atomizing air. There are many different ways in which such air can be preheated, one being effected by the construction shown in Figure 19. The shell or jacket 87 completely surrounds a portion of the outlet manifold 88 of an internal combustion engine, so that the air to be preheated can enter through the opening 89 to receive the heat through the walls of said manifold and enter the gasifying unit through the outlet 90. Other preheaters including various types of burners, can similarly be employed in conjunction with this invention.

It is obvious that our invention is adaptable to many uses in addition to its employment in internal combustion engines, such as in conjunction with open gas burners, industrial and domestic furnaces and such illuminating devices as the Welsbach mantle. Other and additional forms of apparatus and adaptations of the process can be employed beyond and in addition to those hereinbefore described, all within the scope of the appended claims.

What we claim is:

1. In an apparatus for converting a liquid fuel into a gaseous fluid, a flow conduit for conducting therein an atomized fuel stream, the conduit progressively expanding in cross-sectional area in a plurality of stages from its inlet to its outlet terminal, an inlet port at each of said stages, certain of said ports containing serrated terminals, and two independent ducts each communicating with a plurality of said ports, one of said ducts being for an atomizing medium and the other for combustion air.

2. In an apparatus for converting a liquid fuel into a gaseous fluid, a flow conduit for conducting therein an atomized fuel stream, the conduit progressively expanding in cross-sectional area in stages from its inlet to its outlet terminal, the said outlet terminal of the conduit having a slightly constricted outlet opening; an inlet port at each of said stages for the admission therethrough of a fluid medium for interpenetration with said stream; and an intermediate passageway between the terminal portion of the conduit and the inlet duct leading to the fuel-consuming device, said passageway being of expanded cross-

sectional area adjacent and partly surrounding said terminal portion and tapering to a reduced diameter at its juncture with the said duct.

3. In an apparatus for converting a liquid fuel into a gaseous fluid, a flow conduit for conducting therein an atomized fuel stream comprising a plurality of longitudinally disposed Venturi tubes with overlapping adjacent ends forming circumferential gaps therebetween, each succeeding 10 venturi being of greater cross-sectional proportions than its preceding one, and two independent ducts each communicating with a plurality of said gaps, the inner overlapped edges of certain of said venturis being serrated.

15. 4. In a method of gasifying a liquid fuel the step of spraying the fuel, introducing into one section of said stream at a plurality of portions thereof an atomizing fluid and progressively expanding said section of the stream, introducing 20 into a succeeding section of the stream at a plurality of portions thereof unheated combustion air and progressively expanding said latter section of the stream during its flow to an outlet terminal.

25. 5. In a method of converting a liquid fuel into a gaseous fluid the steps of spraying the fuel, inducing a flow of the resulting fuel stream through a low pressure region, introducing at such region a fluid medium preheated to a temperature above the vaporization point of the fuel at the prevailing pressure, introducing thereafter unheated combustion air, and progressively expanding the fuel stream co-mixed with the combustion air introduced therein during its flow to 30 an outlet terminal until the stream is of a temperature below the condensation point of the fuel at the prevailing pressure.

35. 6. In a method of converting a liquid fuel into a gaseous fuel the steps of spraying the fuel, introducing a flow of the resulting fuel stream through a plurality of low-pressure regions, introducing at certain of said regions a fluid medium preheated to a temperature above the vaporization point of the fuel at the prevailing pressure, introducing thereafter at a plurality of points along the stream relatively cold combustion air for interpenetration and commingling therewith, and gradually expanding said fuel stream at least throughout the entire portion thereof into which 40 both the preheated fuel medium and the combustion air were introduced until the stream is of a temperature below the condensation point of the fuel at the prevailing outlet pressure.

45. 7. In a method of converting a liquid fuel into a gaseous fluid the steps of first preheating an atomized fuel stream by introducing therein at a plurality of points therealong a relatively hot fluid medium, progressively expanding the resulting mixture, and then cooling the stream by introducing at a predetermined number of points thereafter a plurality of charges of relatively cold air, and progressively expanding the resulting mixture after the admission of each charge of cold air.

50. 8. The method of converting a liquid fuel into a gaseous fluid, comprising, in combination, the steps of spraying the fuel, inducing a flow of the resulting fuel stream in a predetermined direction, increasing the velocity and decreasing the 55 pressure of the said stream at a plurality of points therealong by restricting at such points its cross-

sectional area, introducing a plurality of said points a fluid medium at a temperature above the vaporization point of the fuel at the prevailing pressure, progressively expanding the resulting mixtures after the introduction of said fluid medium at each of said points, introducing thereafter at the remaining of said points relatively cold combustion air for interpenetration and commingling therewith, and progressively expanding the resulting mixtures after the introduction of said combustion air at each of said points. 10

9. In a method of converting a liquid fuel into a gaseous fluid, the steps of spraying the fuel, inducing a flow of the resulting fuel stream through a low-pressure region, introducing at such region a preheated atomizing fluid medium, thereafter diluting the stream at a plurality of points therealong with a cooling fluid medium, and progressively expanding the fuel stream 20 after each introduction of said atomizing medium and said cooling medium and during its flow to an outlet terminal.

10. In a method of converting a liquid fuel into a gaseous fluid the steps of spraying the fuel, inducing a flow of the resulting fuel stream in a predetermined direction and within a confined space, introducing therein at a plurality of sections therealong a fluid medium of a different temperature than that of the stream to cause a contraction of the high temperature or heat-emitting fluid and an expansion of the low temperature or heat-absorbing fluid within the substantially confined region, thereby resulting in an intermingling of the constituents of both fluids, 30 dividing the peripheral portion of the stream at certain of said sections into relatively fine streams, and directing said fine streams in the general direction of the fuel stream. 35

11. In an apparatus for converting a liquid fuel into a gaseous fluid, a flow conduit for conducting therein an atomized fuel stream, the conduit progressively expanding in cross sectional area in a plurality of stages from its inlet to its outlet terminal, an inlet port at each 40 of said stages, and two independent ducts each communicating with a plurality of said ports, one of said ducts being for an atomizing medium and the other for combustion air. 45

12. In a device for subjecting a fuel to the action of a fluid medium for conversion into a gasified fuel stream, the combination of a plurality of longitudinally disposed overlapping Venturi tubes through which the fuel stream is caused to flow, each tube having a restricted section at which the edge of the outlet of the preceding tube is positioned for optimum operation, the outlet end of certain of the tubes being serrated to present outlet edges directed substantially in the said longitudinal direction, where 55 by the said optimum operation is obtained by positioning the said serrated outlet edges at any portion of the said restricted section. 60

13. In a device for subjecting a fuel to the action of a fluid medium for conversion into a gasified fuel stream, the combination according to claim 12 wherein the Venturi tubes are of progressively expanding proportions. 65
